SPREADER STOKER

Earle C. Miller, Worcester, Mass., assignor to
Riley Stoker Corporation, Worcester, Mass., a
corporation of Massachusetts

Application March 18, 1948, Serial No. 15,639

3 Claims. (Cl. 214—18.28)

1

This invention relates to spreader stokers, and more particularly to a stoker having means whereby the operator may determine the quantity of fuel which has been supplied to the furnace in a given time.

The usual spreader stoker comprises a rotatable bladed rotor or distributor to throw fuel (such as coal) through an opening in a furnace wall. Fuel is supplied to the distributor from a hopper by means of a feeding device having suitable provision for adjusting the feeding rate. In order to check on the efficiency of the furnace, and to be sure that the fuel is being properly supplied to the distributor, it is important that the operator should know the rate of fuel feed. In some cases the fuel is delivered to the hopper from an overhead bunker through a downspout, and metering devices have been installed in such downspouts. However, such devices are subject to error because of variations in the fuel level in the hopper at the time of reading the meter. Furthermore, they tend to obstruct the flow of the fuel, and they are exposed to considerable abrasive wear. In many installations no downspouts are employed.

It is accordingly one object of the invention to provide a spreader stoker having simple, inexpensive and accurate mechanism for metering the fuel which is supplied to the stoker distributor.

It is a further object of the invention to provide a spreader stoker having a fuel metering mechanism which will operate in a proper manner for long periods without appreciable wear.

It is a further object of the invention to provide a spreader stoker having a fuel metering mechanism which will operate entirely independently of any downspout or other means employed for filling the stoker hopper.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts,

Fig. 1 is a vertical section through a spreader stoker, taken on the line 1—1 of Fig. 2; and

Fig. 2 is a section taken on the line 2—2 of Fig. 1, partially broken away for clearness of illustration.

The embodiment illustrated comprises a furnace wall 10 having the usual metal front plate 11 and a fuel admission opening 12. On the

2

front of the plate 11 there is mounted a spreader stoker comprising a casing 14 having a horizontal rotatable bladed distributor 15 therein in position to throw fuel rearwardly through the opening 12 into the furnace. Above and in front of the distributor there is mounted a hopper 16, open at the bottom, from which fuel flows by gravity to a substantially horizontal plate 17 spaced therebeneath. A ram 19 is slidably mounted on the top of the plate 17 and arranged to be reciprocated by a rocker arm 20, whereby fuel will be moved rearwardly along the plate 17 and caused to spill from the rear edge thereof onto the distributor 15. In accordance with well-known practice, any suitable means may be employed to control the rate of fuel feed by varying the stroke or speed of the ram 19. The distance between the plate 17 and the lower edge of the rear wall of the hopper determines the depth or thickness of the stream of fuel moving rearwardly. This lower edge is preferably formed by a cut-off plate 22 mounted on the main body of the hopper and constituting the lower portion of the rear hopper wall.

For the purpose of metering the fuel supplied to the distributor 15, a bladed wheel 24 is rotatably mounted behind the plate 22 in position to be driven by the rearwardly traveling fuel stream. Preferably there are two of these wheels 24, spaced a short distance apart axially, and connected by a common horizontal shaft 25. This shaft 25 is rotatably supported in a bearing 26 on the lower end of an upright arm 28 which is pivotally connected at its upper end to a hinge member 29 attached to the plate 22. From this hinge member the arm 28 extends downwardly for a short distance in contact with the rear surface of the plate 22 and thence rearwardly to the bearing 26. The construction is such that the lowermost blades of the wheels 24 normally extend slightly below the plate 22 to engage the fuel stream, but if an excessive force should be applied to these wheels by a foreign body or by a large lump of fuel the arm 28 will swing rearwardly and upwardly, thus avoiding any damage to the parts. The wheels 24 are connected by means of a flexible shaft or cable 30 to a revolution counter 31 of well-known construction mounted on a bracket 32 on one side of the casing 14. This counter is located laterally beyond the hopper 16 where it can be easily read from the firing aisle.

The operation of the invention will now be apparent from the above disclosure. As the ram 19 reciprocates, a stream of fuel from the hopper

16 will move rearwardly in an intermittent manner along the plate 17 and fall from the rear edge thereof onto the rapidly revolving distributor 15, which will throw the fuel through the opening 12 into the furnace. This fuel stream will be of a predetermined width and of a predetermined depth, the width being a function of the casing width, and the depth being a function of the distance between the plate 17 and the lower edge of the plate 22. The upper portion of the fuel stream will engage the bladed wheels 24 and rotate them, the number of revolutions being recorded by the counter 31. It is a simple matter to calibrate the apparatus by weighing the fuel required to produce a given number of revolutions of the wheels. Thereafter, with the stokers in service, the operator can easily ascertain the feeding rate by noting the change in the reading of the counter 31 over a known interval of time. It is found that the apparatus provides accurate metering of the fuel despite considerable variation in the feeding rate. Furthermore, changes in the moisture content of the fuel have no pronounced effect on the accuracy of the metering. The hinged mounting of the arm 28 protects the wheels 24 from damage by foreign bodies or large lumps of fuel. If the stoker is shut down by stopping the ram 19, the operator can swing the arm 28 upwardly and rearwardly to move the wheels 24 out of the path of radiant heat from the opening 12.

The apparatus is simple, inexpensive, and well adapted for its intended purpose.

Having thus described my invention, what I claim as new and desire to secure by Letters Patent is:

1. A spreader stoker comprising a rotatable fuel distributor, a fuel hopper located above and in front of the distributor, mechanism to feed fuel rearwardly from the bottom of the hopper to the distributor in a stream of predetermined width and depth, a rotatable bladed wheel in position to engage the upper portion of the stream and to be driven thereby, and mechanism connected to the wheel to count the revolutions thereof, said wheel being mounted for movement about an axis parallel to and spaced from its axis of rotation.

2. A spreader stoker comprising a fuel distributor rotatable about a horizontal axis, a substantially horizontal plate located above and in front of the distributor, a fuel hopper located above the plate and having a rear wall with its lower edge spaced from the plate, a ram reciprocable in a forward and rearward direction beneath the hopper to feed fuel along the plate rearwardly from the hopper and beneath the lower edge of the said rear wall in a stream of predetermined width and depth, the stream spilling from the rear edge of the plate onto the distributor, a bladed wheel rotatable about a horizontal axis behind the hopper and extending slightly below the said lower edge in position to be rotated by its engagement with the upper portion of the fuel stream, and a revolution counter connected to the wheel, said wheel being mounted for movement about an axis parallel to and spaced from its axis of rotation.

3. A spreader stoker as set forth in claim 2, in which the wheel is rotatably supported on the lower end of an upright arm which is pivotally connected at its upper end to the rear wall of the hopper, the revolution counter being connected to the wheel by a flexible shaft, and the arm being free to swing rearwardly and upwardly if an excessive force is applied to the wheel by the fuel stream.
